UNITED STATES PATENT OFFICE.

HERMAN C. MUELLER, OF MILWAUKEE, WISCONSIN, ASSIGNOR TO EVINRUDE MOTOR COMPANY, OF MILWAUKEE, WISCONSIN, A CORPORATION OF WISCONSIN.

MAGNETO-ARMATURE.

1,169,179.

Specification of Letters Patent. Patented Jan. 25, 1916.

Application filed June 1, 1915. Serial No. 31,353.

To all whom it may concern:

Be it known that I, HERMAN C. MUELLER, a citizen of the United States, residing at Milwaukee, county of Milwaukee, and State 5 of Wisconsin, have invented new and useful Improvements in Magneto-Armatures, of which the following is a specification.

My invention relates to improvements in magneto armatures.

10 The object of my invention is to provide a form of armature peculiarly adapted to the requirements of that class of small magneto generators in which the armature is supported within a rotating field, the field magnets being adapted for attachment to or forming a part of a fly wheel.

More specifically my object is to provide means whereby the armature may be connected with a supporting disk, through the 20 axis of which the driving shaft of the generator extends, the armature being of such form that it extends around the shaft on one side and supports its pole pieces at diametrically opposite points, whereby the armature 25 may be removed, repaired and replaced without disturbing the field.

In the drawings, Figure 1 is a side view of the stationary member of a magneto generator including my improved armature. 30 Fig. 2 is an edge view of the same.

Like parts are identified by the same reference characters in both views.

A disk 1 is provided with a central aperture 2, through which a driving shaft may 35 extend, the disk being designed to be loosely supported upon the shaft and held in a relatively stationary position. It is provided with a projecting handle whereby it may be adjusted for timing purposes. Armature 40 head pieces 3 and 4 are secured to the disk 1 by bolts, rivets or other suitable fastenings 5. These head pieces are connected with each other by an elbowed or V-shaped core 6. The elbow of the core is covered by a triangular 45 filler block 8, which also serves as a connector, the same being formed to embrace the core and being secured to the disk 1 by fastenings 9. Similar filler blocks 10 are employed in the space between the windings 11 and the head pieces 3 and 4 respectively. These filler blocks 8 and 10 constitute the heads of a set or pair of spools, 50 of which the core 6 constitutes the axes and

upon which the windings 11 are carried. The core 6 and the head pieces 3 and 4 may 55 be integrally formed and may be secured to or detached from the disk 1 without removing the latter from a shaft extending through the aperture 2, although the head pieces 3 and 4 are located at diametrically 60 opposite points with reference to the axis and shaft.

I claim—

1. A magneto armature, comprising a supporting centrally apertured disk, in combination with armature head pieces secured to the outer marginal portions of said disk at diametrically opposite points, an elbowed core extending around said aperture and connecting the head pieces, a supporting and 65 spacing member connecting the elbowed portion of the core with the disk, and windings upon the core on each side of said member between it and the head pieces. 70

2. A magneto armature, comprising a supporting centrally apertured disk, in combination with a V-shaped armature core having a winding upon each leg thereof, and connected with the disk between the windings, head pieces connected with said core 80 and located upon said disk at points diametrically opposite each other.

3. A magneto armature, comprising a supporting centrally apertured disk, in combination with a V-shaped armature core having a winding upon each leg thereof, and connected with the disk between the windings, head pieces connected with said core and located upon said disk at points diametrically opposite each other, and a set of 85 triangular spacers between the windings and the respective head pieces. 90

4. A magneto armature, comprising a supporting centrally apertured disk, in combination with a V-shaped armature core, having a winding upon each leg thereof and connected with the disk between the windings, and head pieces connected with said core and located upon said disk at points diametrically opposite each other, said head 95 pieces and core being integrally formed. 100

5. A magneto armature, comprising a supporting centrally apertured member, a set of armature head pieces secured to said supporting member on diametrically opposite 105 sides of said aperture and provided with

segmentally curved outer surfaces, an el-
bowed core extending around said aperture
on one side and connecting said head pieces,
a spacing connector securing the elbowed
portion of said core to the supporting mem-
ber, and a winding between the spacing con-
nector and each head piece.

In testimony whereof I affix my signature
in the presence of two witnesses.

HERMAN C. MUELLER.
